UNITED STATES PATENT OFFICE.

EMERY H. FAHRNEY, OF OAK PARK, ILLINOIS.

CARBURETER.

1,178,064.

Specification of Letters Patent.

Patented Apr. 4, 1916.

Application filed November 26, 1915. Serial No. 63,571.

To all whom it may concern:

Be it known that I, EMERY H. FAHRNEY, a citizen of the United States, residing at Oak Park, in the county of Cook and State 5 of Illinois, have invented a new and useful Improvement in Carbureters, of which the following is a specification.

This invention relates particularly to carbureters for internal combustion engines 10 utilizing a liquid fuel, such as gasolene.

The primary object of the invention is to provide simple and efficient means for automatically regulating the position of the valve which controls the admission of 15 hydrocarbon fuel to the mixing chamber.

The invention is illustrated, in its preferred embodiment, in the accompanying drawing, in which—

Figure 1 represents a vertical sectional view of a carbureter constructed in accordance with the invention; Fig. 2, a horizontal sectional view taken as indicated at line 2 of Fig. 1; Fig. 3, a vertical sectional view of a cam which serves to automatically vary 25 the position of the needle valve controlling the passage or nozzle leading from the fuel chamber; and Fig. 4, a similar view, showing a slight modification of the cam.

In the embodiment illustrated, A represents the float-chamber of a carbureter, which may conveniently be of circular form in horizontal cross-section; B, a top for the chamber A, which is formed with a shallow chamber B¹; C, a tubular member which 30 extends through the chamber A and affords a vertical main air-intake passage C¹, the member C being provided interiorly with a cross-piece or bridge C², which carries the nozzle C³; D, an auxiliary air valve controlling the admission of additional air to the chamber B¹; E, a conduit connected with the member B and communicating with the chamber B¹, the member E being carried by a conduit-section E¹, which connects with 35 the manifold of the engine and which is equipped with a throttle-valve E²; F, a needle-valve controlling the passage of liquid fuel from the nozzle C³, the needle-valve having a threaded shank portion 40 engaging the threaded bore of a fixed sleeve 2, which forms a part of a bridge-piece disposed in the upper portion of the passage C¹ and which is formed integral with the

upper portion of the sleeve C; G, a cam sleeve provided interiorly with a spiral rib 55 or spline 3, which engages a vertical groove in the peripheral portion of an automatically actuated disk or follower 4, which is 60 slideable vertically on the squared shank portion 5 of the needle-valve F and yieldingly held in a depressed position by a coil-spring 6, the tension of which is adjustable by means of a nut 7 having screw connection with the reduced upper portion of the shank of the needle-valve, the shank of the needle-valve also having a further reduced extension 8, which moves in a vertical guide 9 formed in a spider 10 with which the upper portion of the member E is provided; and H, a valve controlling the admission of fuel 15 to the chamber A, the valve H being actuated by a lever H¹, controlled by a float H² located in the chamber A.

The form of the parts of the carbureter and the construction may be varied greatly. 75 In the form of embodiment selected for illustration of the invention, the chamber A has a cylindrical vertical wall surmounted by the top B, and has a curved bottom wall 11 provided with a central vertical opening. 80

The member C has a flange 12 near its upper end and a threaded reduced extension above said flange, which is screwed into an interiorly threaded opening tapping the bottom of the chamber B¹; and the member 85 C is provided near its lower end with a flange 13, beneath which is a reduced extension 14, which extends through the opening in the bottom 11, the extremity of the portion 14 being threaded and fitted with a 90 nut 15. A gasket 16 is interposed between the flange 13 and the bottom wall 11 of the chamber A. The cross-member C² is provided with an oil passage 17, which 95 communicates at its ends with the interior of the chamber A, and which is intercepted centrally by the vertical passage 18 of the nozzle C³. At the upper end of the nozzle C³ is a conical seat for the valve F.

The top member B is of suitable form to 100 close the upper end of the float chamber, and is provided with the embossment 19 in which the chamber or passage B¹ is formed.

The auxiliary valve D may be of any suitable form. As shown, it comprises a disk 105 20 which is provided with a stem 21, work-

ing through the spider 22 of an annular nut 23, which has screw connection with the embossment 19 of the top member B. The stem is encircled by a coil-spring 24 adjustable by means of a nut 25, connected with the upper end of the stem 21.

The member E is provided near its lower end with a flange 26, which bears upon the upper surface of the embossment 19; and the member E has an extension 27 which fits snugly in a bore provided in the upper wall of the chamber B¹.

The valve F, controlling the discharge of the nozzle or jet C³, may be of any approved form. The threaded portion 1 of the valve stem should turn freely in the threaded bearing 2, which constitutes the hub portion of a spider 2² formed in the upper portion of the conduit C.

20 The sleeve G is fixedly secured in the lower portion of the conduit E and is capable of angular adjustment. It is confined in the enlarged lower portion of the conduit E by a threaded ring or nut 28; and, as shown in Fig. 2, it is provided peripherally with a series of recesses or sockets 29 adapted to receive an implement, by means of which the sleeve may be adjusted or turned within the conduit. To afford access, the 30 conduit E is provided with a segmental slot 30, guarded by a closure 31, which may be moved out of the way to give access to the slot. The sleeve G is secured in adjustable position by means of a set-screw 32.

35 The cam-rib 3 may be formed integrally with the inner surface of the sleeve G. It may be in the form of a spiral of very high pitch, as indicated. It engages a peripheral notch 3^a with which the disk 4 is provided; and the cam-rib 3 and notch or groove 3^a may be regarded as cam connections between the disk 4 and the sleeve G, which, in turn, is fixed to the wall of the conduit E.

The passage through the members C and 45 E and the intervening portion of the chamber B¹ may be regarded as the air conduit or mixing chamber of the carbureter, communicating through the member E with the engine, or with the manifold of the engine; 50 and, as indicated above, the chamber B¹ also affords a lateral air intake, the admission to which is controlled by the auxiliary valve D. The bridge piece C² of the member C has depending therefrom a threaded stem 55 33, upon which is adjustably mounted an air regulating device 34, by means of which the main admission port 35 of the carbureter is regulated.

The valve H controls an oil admission 60 passage 36, with which communicates a pipe 37 leading from the oil reservoir. The construction of the valve H, the lever H¹ and float H², may be of any approved design.

In the illustration given, the lever H¹ is 65 connected with a pivot 38 carried by lugs

39 depending from the top member B of the fuel chamber A. As is well understood, the valve H operates to maintain a constant head of oil in the chamber A.

In the carbureter illustrated, the chamber 70 containing the gasolene is of annular form, the detachable tubular member C forming the inner wall of the annulus. In this design, a vertical air passage wholly through the carbureter is afforded.

75 In Fig. 4, G¹ represents a sleeve equipped interiorly with a cam-rib 3^b. The construction is similar to the construction shown in Fig. 3, except that the pitch of the cam-rib is varied, becoming greater or steeper at the upper portion, so that the needle-valve F, when this form of cam-rib is employed, will be rotated less as the follower 4 approaches the upper end of the cam-rib. In practice, the cam-rib will be given such inclination or 80 pitch, in its various portions, as will give the best results for the particular engine to which the carbureter may be applied.

85 The operation of the carbureter is as follows: The desired tension upon the spring 6 is secured by adjustment of the nut 7. The sleeve G is angularly adjusted and initially set in such position as to hold the valve F open the proper distance to supply 90 the oil needed for low speed of the engine. As the throttle-valve E² is opened the speed of the engine increases, thereby increasing the suction in the conduit E. The increased 95 velocity of the mixture passing through the conduit E causes the follower 4 to rise 100 against the pressure of the spring 6, the follower sliding on the squared or splined portion 5 of the stem of the valve F. As the follower 4 rises, it is caused to rotate through the medium of the cam-rib 3, thereby turning the needle-valve in its threaded bearing 2, causing the valve to open to admit an increased amount of gasolene to the 105 mixing chamber. When the engine slows down, the spring then depresses the follower 110 4, thus turning the valve in the opposite direction and causing it to return to the slow-speed position. As has been indicated, the various portions of the cam-rib may be given such inclination as will secure the 115 proper mixture at various speeds of the engine.

The construction described is simple, and enables certainty of results to be obtained, it being understood that the cam-rib 3 is rigid 120 and so designed as to turn the needle-valve with precision.

The foregoing detailed description has been given for clearness of understanding only, and no unnecessary limitation should 125 be understood therefrom, but the appended claims should be construed as broadly as is permissible in view of the prior art.

What I claim as new and desire to secure by Letters Patent is:

1. In a carbureter, the combination of an air conduit and fuel-supply chamber provided with a discharge passage communicating with said conduit, a valve controlling said discharge passage whose stem has threaded engagement with a fixed part of the carbureter, a suction-operated follower slidably splined on said stem, and cam connections between said follower and the wall of the conduit, whereby the valve will be turned and automatically adjusted. 5
2. In a carbureter, the combination of an air conduit provided interiorly with a threaded bearing, a valve having a threaded stem working in said threaded bearing, a fuel-supply chamber provided with a discharge passage communicating with said conduit and guarded by said valve, a suction-operated follower splined on the stem 10 of said valve, and cam connections between said follower and a wall of the conduit, whereby the valve will be turned and adjusted by the movement of said follower. 15
3. In a carbureter, the combination of an air conduit, a fixed threaded bearing therein, a valve having a threaded stem working in said threaded bearing, a fuel supply chamber provided with a nozzle located in said conduit and guarded by said valve, a suction-controlled member in said conduit above said threaded bearing, and connections between said member and the stem of said valve and between said member and the wall of said conduit, whereby the valve will be turned and adjusted in said threaded bearing by the movement of said suction-controlled member. 20
4. In a carbureter, the combination of an air conduit, a fixed threaded bearing therein, a valve having a threaded stem engaging said bearing, a follower slidably and non-rotatably mounted on the stem of said valve above said threaded bearing, a spring engaging said follower, cam connections between said follower and a wall of said conduit, whereby the follower will be rotated in its rising and falling movements, and a fuel supply chamber provided with a discharge nozzle disposed in said conduit and 25 guarded by said valve. 50
5. In a carbureter, the combination of a fuel chamber having a central air passage therethrough, a chamber above the fuel chamber communicating with said air passage and equipped with an auxiliary air-intake valve, a conduit above said chamber leading to the engine, a nozzle in said first named passage communicating with the fuel supply chamber, a fixed threaded bearing above said nozzle, a valve having a threaded stem working in said threaded bearing and guarding said nozzle, a suction-controlled member in the conduit above said threaded bearing and serving to rotate said valve in 30 its threaded bearing, and cam connections 55 between said suction-controlled member and a wall of the conduit. 60
6. In a carbureter, the combination of an air conduit, a fuel-supply chamber provided with a discharge passage communicating with said conduit, a valve controlling said discharge passage whose stem has threaded engagement with a fixed part of the carbureter, a suction-controlled follower splined on the stem of said valve, and an angularly adjustable member in said conduit equipped with a cam-rib adapted to rotate the follower in the rising and falling movements of the follower. 70
7. In a carbureter, the combination of an air conduit, a sleeve located in said conduit and angularly adjustable therein, a fixed threaded bearing in the conduit below said sleeve, a valve having a threaded stem working through said threaded bearing, a follower having splined connection with the stem of the valve and cam connections with said sleeve, and a fuel-supply chamber provided with a discharge nozzle located in said conduit beneath said threaded bearing and 75 guarded by said valve. 80
8. In a carbureter, the combination of an annular fuel chamber having an air passage through its central portion and provided with a discharge nozzle located in said air 85 passage, a threaded bearing in the upper portion of said air passage, a valve guarding said nozzle and having a threaded stem working in said threaded bearing, an air chamber surmounting the fuel-supply chamber and provided with an auxiliary air intake, a conduit leading to the engine and communicating with said air chamber, a spring-held follower having splined connection with the valve stem above said 90 threaded bearing, and cam connections between said follower and a wall of said conduit. 95
9. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 100
10. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 110
11. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 115
12. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 120
13. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 125
14. In a carbureter, the combination of a fuel supply chamber having an opening through its lower wall, a top for said fuel-supply chamber provided with an air chamber, a sleeve forming the inner wall of the fuel-supply chamber and connecting the top and bottom walls of the fuel supply chamber, said sleeve communicating at its upper end with said air chamber at its lower end with the atmosphere, an auxiliary valve controlling admission to said air chamber, a nozzle in said sleeve communicating with the interior of the fuel-supply chamber, a threaded bearing at the upper portion of said sleeve, a valve guarding said nozzle and having a threaded stem working in said threaded bearing, a conduit communicating with said air chamber, a spring-held follower having splined connection with the stem of the valve, and cam connections between said follower and the wall of said conduit. 130

10. In a carbureter, the combination of an air conduit, a fuel-supply chamber provided with a discharge passage communicating with said conduit, a valve controlling said discharge passage, a suction-controlled member in said conduit controlling the position of said valve, and cam connections between

said member and a wall of said conduit, including a spiral member having variations in its pitch.

EMERY H. FAHRNEY.
